US0D1048798S

(12) **United States Design Patent** (10) **Patent No.:** **US D1,048,798 S**
(45) **Date of Patent:** ** *Oct. 29, 2024

(54) **OVEN**

- (71) Applicant: **SharkNinja Operating LLC**, Needham, MA (US)
- (72) Inventors: **Joshua D. Anthony**, North Billerica, MA (US); **Nicholas Varjabedian**, Taunton, MA (US); **Dan Kestenbaum**, Brookline, MA (US)
- (73) Assignee: **SharkNinja Operating LLC**, Needham, MA (US)
- (*) Notice: This patent is subject to a terminal disclaimer.

(**) Term: **15 Years**

(21) Appl. No.: **29/870,586**

(22) Filed: **Jan. 31, 2023**

Related U.S. Application Data

- (62) Division of application No. 29/694,047, filed on Jun. 6, 2019, now Pat. No. Des. 977,297.

(57) **CLAIM**

The ornamental design for an oven, as shown and described.

DESCRIPTION

FIG. 1 is a perspective view of an oven, showing our new design;

FIG. 2 is a front view thereof;

FIG. 3 is a rear view thereof;

FIG. 4 is a side view thereof;

FIG. 5 is another side view thereof;

FIG. 6 is a top view of thereof; and,

FIG. 7 is a bottom view thereof.

The evenly broken lines are shown for the purpose of illustrating parts of the oven that form no part of the claimed design.

The dash-dot broken lines represent boundary lines that form no part of the claimed design.

1 Claim, 6 Drawing Sheets
